UNITED STATES PATENT OFFICE.

GEORGE J. J. HOELSCHE, OF ALLEGHENY, PENNSYLVANIA.

HAND BRICK-CARRIER.

SPECIFICATION forming part of Letters Patent No. 680,591, dated August 13, 1901.

Application filed December 7, 1900. Serial No. 39,034. (No model.)

To all whom it may concern:

Be it known that I, GEORGE J. J. HOELSCHE, a citizen of the United States of America, residing at Allegheny, in the county of Allegheny and State of Pennsylvania, have invented certain new and useful Improvements in Hand Brick-Carriers, of which the following is a specification, reference being had therein to the accompanying drawings.

This invention relates to certain new and useful improvements in brick-carriers, and has for its object the provision of novel means whereby a number of bricks may be easily held together and conveyed from one place to another.

The invention further aims to construct a device of the above-described character that will be extremely simple in its construction, strong, durable, and comparatively inexpensive to manufacture, and, furthermore, one that will be highly efficient in its operation.

Another object of the invention is to construct a device in such a manner that it may be easily adjusted to fit any number of rows of bricks that are desired to be conveyed at a time from place to place.

With the above and other objects in view the invention consists in the novel combination and arrangement of parts to be herein-after more fully described, and specifically pointed out in the claims.

In describing the invention in detail reference is had to the accompanying drawings, forming a part of this specification, and wherein like numerals of reference indicate corresponding parts throughout the several views, in which—

Figure 1 is a perspective view of my improved brick-carrier. Fig. 2 is a side view thereof, partly in vertical section. Fig. 3 is an end elevation of the same.

In the drawings the reference-numerals 1 and 2 indicate a pair of L-shaped clamps, the latter terminating in outwardly-extending portions 3, said clamps having formed therein screw-threaded openings 4, the clamp 1 being provided with a right-hand screw-threaded opening and the clamp 2 with a left-hand screw-threaded opening for the reception of screw-threaded rods 5, which are also screw-threaded in opposite directions to register with the screw-threaded openings 4. Said

screw-threaded rods carry upwardly-extending portions 6 and terminate in apertured lugs 7 for the reception of a pair of tongs 8, 55 the jaws 9 of which engage in the apertured lugs 7. The said tongs are further provided with a handle 10.

The reference-numeral 11 indicates inwardly-extending semicircular lugs which 60 are formed integral with the upwardly-extending portions 6 and are arranged in close proximity to the apertured lugs 7. The L-shaped clamps 12 are further provided with handles 12, which are rigidly secured thereto and are 65 arranged on the top face of said L-shaped clamps near the downwardly-extending portion.

The reference-numeral 14 represents semi-circular shields which are connected by means 70 of set-screws 15 to the under face of the L-shaped clamps and are adapted to engage the upper edge of the bricks when the carrier is in position as shown in Fig. 3, while the downwardly-extending portions of the L-shaped 75 clamps engage the outer faces of the two end bricks in the row.

The operation of my improved brick-carrier is as follows: The device is adjusted to correspond with the length of the row of 80 bricks by turning the rods in the L-shaped clamps, thereby operating said L-shaped clamps either inwardly or outwardly, as the case may be. The carrier is then placed upon the rows of bricks, and by taking a grasp 85 upon the handle 10 the L-shaped clamps by reason of the tongs will operate sufficiently to firmly engage and clasp the end bricks of the row. The bricks may then be carried to their destination, and by placing the same 90 upon the ground and releasing the hold the carrier will automatically release the bricks sufficiently to allow the same to be removed from the row of bricks. The operation is then repeated. The semicircular lugs serve 95 to limit the inward movement of the tongs and outwardly-extending portions of the screw-threaded rods.

The many advantages obtained by my improved carrier will be readily understood, 100 and it will be noted that various changes may be made in the details of construction without departing from the general spirit of my invention.

Having thus fully described my invention, what I claim as new, and desire to secure by Letters Patent, is—

1. In a brick-carrier, the combination of two L-shaped clamps having arranged therein two oppositely-inclined screw-threaded openings, two oppositely-screw-threaded rods carrying upwardly-extending portions, and tongs engaging said upwardly-extending portions, substantially as described.
2. In a brick-carrier, the combination of two L-shaped clamps having arranged therein two oppositely-inclined screw-threaded openings, two oppositely-screw-threaded rods carrying upwardly-extending portions, tongs engaging said upwardly-extending portions, and handles arranged on each of said L-shaped clamps.
3. In a brick-carrier, the combination of two L-shaped clamps having arranged therein two oppositely-inclined screw-threaded openings, two oppositely-screw-threaded rods

carrying upwardly-extending portions, tongs engaging said upwardly-extending portions, handles arranged on each of said L-shaped clamps, and shields arranged to the under face of said L-shaped clamps. 25

4. In a brick-carrier, the combination of two L-shaped clamps having arranged therein two oppositely-inclined screw-threaded openings, two oppositely-screw-threaded rods carrying upwardly-extending portions, said upwardly-extending portions terminating in apertured lugs, tongs engaging said upwardly-extending portions, handles arranged on each of said L-shaped clamps, and shields arranged to the under face of said L-shaped clamps, substantially as set forth. 30 35

In testimony whereof I affix my signature in the presence of two witnesses.

GEORGE J. J. HOELSCHÉ.
